ATTORNEY

UNITED STATES PATENT OFFICE

EUGENE A. AURELIUS, OF BRAHAM, MINNESOTA, ASSIGNOR OF ONE-HALF TO BERNARD E. AURELIUS, OF BRAHAM, MINNESOTA

EGG BEATER

Application filed October 17, 1930. Serial No. 489,391.

This invention relates to egg beaters, or cream whippers, an object being to provide a device which includes triple beater elements, whereby the time necessary for beating eggs or whipping cream will be materially reduced, novel means being provided for driving the beater elements.

Another object of the invention is the provision of novel means for mounting the beater elements and for mounting the gears which operate said elements together with novel means for mounting the driving gear crank arm.

With the above and other objects in view, the invention further includes the following novel features and details of construction, to be hereinafter more fully described, illustrated in the accompanying drawings and pointed out in the appended claim.

In the drawings:—

Figure 1 is an elevation partly broken away showing a beater constructed in accordance with the invention.

Figure 2 is an enlarged sectional view taken substantially on the line 2—2 of Figure 1.

Figure 3 is an enlarged fragmentary elevation of a portion of the plate or body of the device and illustrating one of the shaft bearings.

Referring to the drawings in detail where in like characters of reference denote corresponding parts, the reference character 10 indicates the body of the device which is in the form of a plate and which has extending from one edge a plurality of rods 11 and 12. These rods are connected at their outer ends by means of a bar 13, while the inner ends of the rods are received in slots that enter from the outer end of the plate 10 and are clamped in said slots by offset portions 14 struck from the plate 10 so that a rigid frame is provided.

Rotatably mounted upon the rods 11 and 12 are beater elements 14 of the type usually found in devices of this character. These beater elements are so arranged that when rotated the offset portions 14' of one beater element will pass between the offset portions 14' of the adjacent beater element.

As shown in the drawings three beater elements are utilized, the intermediate element being mounted upon the rod 11, while the rods 12 are arranged upon opposite sides of the rod 11 so that the beater elements are arranged in a row.

Secured rigidly to the central beater element which operates upon the rod 11 is a master pinion 15. This pinion is relatively wide and is engaged by thin pinions 16 which are fast with the outer beater elements 14, so that rotation of the pinion 15 will operate all of the beater elements.

The plate 10 is provided with an opening 17 and surrounding this opening upon opposite sides of the plate are substantially semi-spherical bearing members 18. These bearing members are flanged as at 19 and rivets 20 which pass through these flanges and through the plate 10 serve to secure the bearing members in place. A sleeve 21 passes through the plate 10 and connects the bearing members 18 and provides a bearing for a shaft 22, while mounted upon this shaft and engaging the master pinion 15 is a crown gear 23. The gear is fast upon the shaft 22 and for this purpose the shaft is provided with an annular shoulder 24 against which bears one end of an arm 25, the latter extending through an opening 26 provided in the gear 23 and having an offset portion 27, to which is secured an operating handle 28. The shaft 22 is headed as shown at 29 and this head binds the gear 23 and the arm 25 against the annular shoulder 24. The shaft 22 thus serves also to secure the arm 25 in position, while by extending this arm through the gear 23, the use of additional fastening devices is eliminated.

A yoke 30 is attached to the plate 10 as shown at 31, and this yoke carries a handle or grip 32 for holding the device when in use.

The invention is susceptible of various changes in its form, proportions and minor details of construction and the right is herein reserved to make such changes as properly fall within the scope of the appended claim.

Having described the invention what is claimed is:—

In an egg beater, comprising a flat plate having a handle attached to one of its ends and its other end provided with a central slot and outer slots, rods having one of their ends received in said slots, and integral offset portions on the plates for clamping the rods in the slots, an outer bar to which the rods are connected and beaters having their ends journaled for rotation on said rods, intermeshing pinions journaled on the rods, and to which the upper ends of the beaters are connected, oppositely disposed semi-spherical bearings on the plate, a bearing sleeve journaled therethrough, a shaft having its opposite ends headed for contact with the opposite ends of the bearing sleeves, a crown gear journaled on the shaft to mesh with the intermediate gear, and an operating handle for the shaft having an arm passed through the crown gear and having an opening for the passage of the shaft therethrough.

In testimony whereof I affix my signature.

EUGENE A. AURELIUS.
